Cora Southworth.

A. M. P. Patent.

The schedule referred to in this Letter Patent and making part of the same containing a description in the words of the said Ezra Southworth, himself of his improvement in making Ink Stand.

To all whom these presents shall come -

Be it known that I, Ezra Southworth of Saybrook in the County of Middlesex & State of Connecticut, have invented a new and useful improvement in making Ink-Stands viz -

Take a piece of wood of proper dimensions & turn, cut or carve it into any shape you please. then bore a hole of sufficient size to contain a Vial. then take a vial of proper dimensions to contain the ink. & place it in the wood, taking care to place around it cotton, wool, flax, hemp, or charcoal, or any other material which tends to prevent it from breaking or freezing then stop the hole with a piece of wood which completely covers the vial in wood, then paint, varnish, and bronze it, and you have an elegant and useful and durable ink Stand, better than has heretofore been used.

The setting of the vials in wood, & securing them from breaking or freezing, by means of cotton, wool, flax, hemp, or charcoal, or any other material, which has that tendency I claim as an entirely new improvement in the making of ink Stand.

In testifying that the foregoing is a true Specification & Schedule of my improvement as above described I have hereunto set my hand, this 10th day of January 1833,

Witness,

Ezra G. Southworth
John G. Southworth
